Primary Examiner — W. A. Teddy Falloway

(74) *Attorney, Agent, or Firm* — Adam K. Sacharoff; Much Shelist, P.C.

(57) **CLAIM**

The ornamental design for a bottle having dual configuration, as shown and described.

DESCRIPTION

FIG. 1 is a front left side perspective view showing the new design for a bottle having dual configuration;

FIG. 2 is a front, bottom side perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof;

FIG. 9 is a front left side perspective view showing another embodiment for the new design;

FIG. 10 is a front, bottom side perspective view thereof;

FIG. 11 is a front elevation view thereof;

FIG. 12 is a rear elevation view thereof;

FIG. 13 is a left side view thereof;

FIG. 14 is a right side view thereof;

FIG. 15 is a top plan view thereof; and,

FIG. 16 is a bottom plan view thereof.

The broken lines shown illustrate portions of the bottle having dual configuration and form no part of the claimed design.

1 Claim, 16 Drawing Sheets
